PICTURE FRAME MOULDING

Johannes Vihma, Toronto, Ontario, Canada, assignor to
Artistic Woodwork Co. Ltd., Downsview, Ontario,
Canada

Filed Nov. 7, 1974, Ser. No. 521,731

Term of patent 14 years

Int. Cl. D6—07

U.S. Cl. D25—74

FIG. 1 is a perspective view of a picture frame moulding showing my new design, a portion thereof being broken away to indicate indeterminate length; and

FIG. 2 is an end elevational view thereof.

I claim:

The ornamental design for a picture frame moulding, as shown and described.
